UNITED STATES PATENT OFFICE.

CHARLES E. TRAXEL, OF ROME, NEW YORK, ASSIGNOR TO ROME WIRE COMPANY, OF ROME, NEW YORK, A CORPORATION OF NEW YORK.

BRAIDING-MACHINE.

1,295,639.

Specification of Letters Patent. Patented Feb. 25, 1919.

Application filed April 7, 1915. Serial No. 19,786.

To all whom it may concern:

Be it known that I, CHARLES E. TRAXEL, a citizen of the United States, residing at Rome, in the county of Oneida and State of New York, have invented an Improvement in Braiding-Machines, of which the following is a specification.

In braiding-machines for covering wire with silk, cotton and other threads, automatic means have been provided for stopping the machine in case a thread breaks, said means usually consisting of a weight adapted to be lifted by the thread when the thread is pulled taut, and arranged to act by gravity when the thread breaks, thereby to control the operation of a stop-motion or clutch for the machine.

The threads are rapidly drawn from supplies arranged on supply-holders, and in Letters Patent #1,058,206, dated April 8, 1913, granted to me, each supply-holder has a tension-device in the form of a friction-brake which engages and exerts a moderate pressure upon it, whereby its rotary motion is resisted, but not positively restrained or checked, and a take-up arm for the thread movement of which is opposed by a spring, is arranged to be engaged by the thread and to be operated by a pull upon the thread, and when raised to a predetermined position to move the friction-brake will relieve the tension on the supply-holder, thus admitting of sudden withdrawals of thread from the supply-holder, which movements are yieldingly resisted, and as a result the thread will not be broken even when the machine is being driven at high speed.

The present invention has for one of its objects the provision of a controlling-member for the stop-motion or clutch-mechanism of the machine, which is arranged to be operated by said take-up arm, in case a thread breaks and said take-up arm resumes its normal position to control the stopping of the machine.

Another object of the invention is the construction of the controlling-member, adapting it to be moved positively in both directions by the take-up arm.

Figure 1, is a side-elevation of a traveling-carrier for braiding-machines embodying this invention, the take-up arm being in partial elevated position.

Fig. 2, is a front elevation of the same.

Fig. 3, is a detail showing the take-up arm

in full elevated position with the friction-brake disengaged.

Fig. 4, is a similar detail showing the take-up arm in its normal or lowermost position, and the controlling-member for the clutch-mechanism, operated to cause disengagement of the clutch.

Fig. 5, is a plan view of the traveling-carrier (the supply-holder being removed) and clutch-mechanism.

Fig. 6, is a side elevation of the parts shown in Fig. 5 with the supply-holder arranged in position.

Figs. 7 and 8, are different views of a traveling-carrier having a modified form of friction-brake.

10 represents the traveling-carrier, 12 a post thereon, 13 a supply-holder rotatably mounted on said post, said supply-holder having a circularly formed base 14. Suitable means are or may be arranged at the top of the post to prevent axial movement of the supply-holder. 40 represents the take-up arm for the thread 41, and has a hook 42, or other means at its extremity for engagement with the thread, which thread passes over a hook or other means arranged on an upright post 35 on the traveling-carrier. Said take-up arm is secured to a pivot-shaft 43, which extends through a hole in an arm 70, and which has arranged on it a spring 44, attached at one end to it, and at the other end to said arm 70, said spring acting to move the take-up arm in a downward direction, and thus oppose its upward movement due to a pull upon the thread.

The end of the spring may be adjustably attached to the pivot-shaft, as for instance, by arranging a disk 45 on said shaft, having notches in its periphery, and arranging the end of the spring in any of said notches.

The take-up arm, as here shown, has a projection 46 arranged to engage a projection 47, on the carrier-frame to limit its upward movement. Also, as here shown, it has a projection 48 arranged to engage the controlling-member of the stop-motion or clutch of the machine. Said controlling-member is made as a bell-crank lever comprising an upright arm 60, and a laterally extended arm 61, and is pivoted to the carrier-frame at 62. It also has a heel-extension 63, for limiting its movement in one direction, see Fig. 3, and its movement in the other direction is limited by the upper end 110.

of its arm 60, striking against the side of the arm 70 or any other stop, see Fig. 4. Its laterally extended arm 61, has a forward projection or ear 64.

- 5 When the take-up arm is in its lowermost position, see Fig. 4, it engages the projection 64, and is thereby prevented from further movement, and the projection 48, on said arm extends over the top of the 10 projection 64, and thus acts to prevent movement of the controlling-member into its other position. The take-up arm and controlling-member will occupy these positions when the thread breaks. When the take-up 15 arm is lifted by a pull upon the thread, see Figs. 1 and 3, its projection 48 is moved into engagement with the side of the upright arm 60, and acts to move the controlling-member on its pivot, thereby to raise the 20 projection 64, to permit engagement of the clutch; and said controlling-member will be positively held in this position during the time the take-up arm is thus lifted, but when the thread breaks and the take-up arm 25 resumes its normal or lowermost position, its projection 48 will engage and positively move the laterally extended arm 61, thus moving the controlling-member on its pivot. The projection 64 is thus moved into position to cause disengagement of the clutch. It will be observed that the controlling-member is moved positively in both directions, and also is positively held in both of its 30 positions.
- 35 One form of stop-motion is here shown for the purpose of illustrating one embodiment of my invention which is arranged to be controlled by the controlling-member here shown.
- 40 Referring to Figs. 5 and 6, the projection 64 of the controlling-member is arranged for engagement with the curved end-portion 65, of a holding lever pivotally mounted on a stud 66, the other end-portion of which 45 lever has a latch-formed extremity 67, for engagement with a pivoted clutch-lever 68. The clutch-lever has a spring 69 attached to it by which it is moved to slide the clutch-member, and thereby disengage the clutch, 50 and said clutch lever is adapted to be held in clutch-engaging position by the holding-lever with the latch-formed end which engages it, and to be moved by its actuating-spring when said holding-lever is moved out 55 of engagement with it. Said holding-lever has a spring 91 connected with it to provide a yielding connection for it. When the controlling-member, which is operated by the take-up arm, is in its elevated position, as 60 represented in Figs. 1 or 3, its projection 64 occupies a path of movement above the curved end-portion 65 of the holding-lever, in consequence of which said holding-lever is held in engagement with the clutch-lever, 65 thereby to hold said lever in clutch-engaging

position. When the thread breaks and the take-up arm resumes its normal position said controlling-member is moved, and its projection 64 enters a path of movement for engagement with said curved end-portion, 70 and upon engaging said portion, acts to move the holding-lever to disengage the clutch-lever and permit disengagement of the clutch.

Thus it will be seen that the clutch-lever 75 may be moved by hand into clutch-engaging position, and the machine started, and that said lever will be held in such position by the holding-lever, which is arranged for engagement with the controlling-member, 80 adapted to be operated by the take-up arm when the thread breaks, thus automatically stopping the machine.

The arm 70, to which the take-up arm is pivotally connected, is here shown as the pivoted supporting-member for the friction-brake for the supply-holder. Referring to Figs. 1 to 6, the friction-brake is constructed and arranged for co-operation with a metallic supply-holder having a circularly formed 90 base with a corrugated flange, the inside of the flange being employed as the brake-engaging surface. In the structure shown in said figures, the arm 70 is pivoted at its lower end to an ear on the carrier frame, and has a projection 71 at its upper end which is adapted to engage the side of the corrugated flange, and said arm 70 is movable in the direction toward the left, Fig. 1, by the spring 44, thereby to engage said flange. 100 The force of such engagement is gradually increased as the take-up arm is lifted until such time as said arm is positively moved out of engagement with the flange. The take-up arm has a projection 72 arranged 105 near its pivot, which, when said arm is raised high enough, will engage a fixed pin 73, on the carrier-frame, and by further movement and consequent pressure upon said pin, said arm 70 is moved on its pivot in the direction 110 toward the right Fig. 3; and its projection 71 moved out of engagement with the corrugated brake-engaging surface. It will be noted that, as one end of the spring is attached to the pivot shaft and the other end 115 to the arm 70, that, when said spring is adjusted rotarily and the pivot shaft turned by the take-up arm, the force exerted by the spring will have a tendency to move the arm 70 on its pivot in a direction toward the left 120 of Fig. 1. The tension of the spring is sufficient to act to move said arm 70 in such manner not only when the take-up arm is lifted, but also when the take-up arm is moved into its lowermost position, due to thread breakage, as shown in Fig. 4. However, in so far as the operation of the controlling-member for the clutch-mechanism by the take-up arm is concerned, the friction-brake may be omitted, or, if employed, may be constructed 125 130

in any other manner, hence a modified form of friction-brake is represented in Figs. 7 and 8, which is adapted for a supply-holder of another type. In this instance, the supply-holder has a circularly formed base with notches on its under side, and the member 70, to which the take-up arm is pivoted, has an extension arm 80, with a projection 81, thereon, arranged for engagement with and 10 disengagement from the notches. It is obvious that the operation of the parts is the same when the thread runs out as when the thread breaks.

I claim:—

15 1. In a braiding-machine, the combination of a clutch-mechanism for the machine, a traveling-carrier, a controlling-member pivotally supported on said carrier and arranged to control the operation of said 20 clutch-mechanism, and a take-up arm for the thread, borne by said carrier and arranged to move said controlling-member into and out of position for engagement with the clutch operating mechanism.

25 2. In a braiding-machine, the combination of a clutch-mechanism for the machine, a traveling-carrier, a two-armed controlling-member borne by said carrier and arranged to control the operation of said clutch-mechanism, a pivoted take-up arm for the thread 30 borne by said carrier, said take-up arm engaging one arm of the controlling-member to move the other arm of said member into and out of the path of the clutch-mechanism.

35 3. In a braiding-machine, the combination of a clutch-mechanism for the machine, a traveling-carrier, and a pivoted controlling-member borne by said carrier comprising an upright arm and a laterally extended arm 40 with a forward projection, and a take-up arm for the thread, borne by the carrier, having a projection thereon for engagement, respectively, with the arms of said controlling-member, the forward projection of said 45 controlling-member being arranged for controlling the clutch-mechanism.

4. In a braiding-machine, the combination with the clutch-mechanism for the machine, and actuating-means therefor, of holding 50 means arranged to hold said actuating-means in condition to operate, a traveling-carrier, a controlling-member for said holding-means borne by said carrier, a take-up arm adapted for engagement with thread, in the upward and downward paths of movement of which said controlling-member is 55 arranged, and a spring to oppose upward movement of said arm.

5. In a braiding-machine, the combination 60 of a rotatable supply-holder, a traveling-carrier therefor, a friction-brake borne by said carrier and arranged for engagement with the supply-holder, and a take-up arm adapted for engagement with the thread ar- 65 ranged to actuate said friction-brake to re-

lieve the pressure on the supply-holder by a pull upon the thread, a spring to oppose movement of the arm, and a controlling-member for stopping the machine, arranged in the upward and downward paths of movement of said take-up arm to be operated when said arm is moved. 70

6. In a braiding machine, a carrier comprising a rotatable supply holder provided with a corrugated portion, a member having 75 a projection, means for moving said member with its projection into engagement with said corrugated portion, a take-up arm arranged on said member, an abutment, said take up arm having means for engaging 80 said abutment to move said member and disengage the projection from the corrugated portion.

7. In a braiding machine, a carrier comprising a rotatable supply holder provided with a corrugated portion, a pivoted member having a projection, said member being movable to cause its projection to engage and disengage said corrugated portion, an abutment, a spring-pressed take-up arm 90 pivotedly supported on said member, having a projection adapted to engage said abutment when in an elevated position to move said member to cause its projection to disengage the corrugated portion. 95

8. In a braiding machine, a carrier comprising a rotatable supply holder provided with engaging portions, a member having a projection adapted to engage said engaging portions, a pivoted spring-pressed take-up arm adapted when raised to a predetermined height, to move said member to disengage the supply holder, a clutch-mechanism for the stop-motion mechanism, a controlling-member for the clutch-mechanism. 100 and means carried by said take-up arm and adapted upon upward movement of the arm to move said controlling member in one direction and upon a dropping of the arm a predetermined distance to engage and move 105 said controlling-member to operate the clutch-mechanism. 110

9. In a braiding machine, a carrier comprising a rotatable supply holder provided with engaging portions, a member having a 115 projection adapted to engage said engaging portions, a pivoted spring-pressed take-up arm adapted when raised to a predetermined height, to move said member to disengage the supply holder, a clutch-mechanism for the stop-motion mechanism, a controlling-member, a lug carried by said take-up arm adapted upon upward movement of the arm to engage and move said controlling-member in one direction and upon downward 120 movement of the arm to engage and move said controlling-member in the other direction to operate the clutch-mechanism.

10. In a braiding machine, a carrier comprising a rotatable supply holder, a pivoted 130

- take-up arm, restraining-means for the supply holder adapted to be operated by said arm when raised to a predetermined elevation, a clutch-mechanism for the stop-motion mechanism, a pivoted controlling-member for said clutch-mechanism adapted to be operated by said take-up arm into and out of position for engagement with the clutch mechanism.
- 10 11. In a braiding machine, a carrier comprising a rotatable supply holder, a pivoted take-up arm, restraining-means for the supply holder adapted to be operated by said arm when raised to a predetermined elevation, a clutch-mechanism for the stop-motion mechanism, a pivoted bell-crank lever, one arm of which is arranged to control the clutch-mechanism and both arms of which are arranged to be engaged by said take-up arm.
- 15 12. In a braiding machine, a carrier comprising a rotatable supply holder, a pivoted take-up arm, restraining-means for the supply holder adapted to be operated by said arm when raised to a predetermined elevation, a clutch-mechanism for the stop-motion mechanism, a pivoted controlling-member for the clutch-mechanism having a cam surface and a lug carried by said take-up arm adapted to engage said cam surface to
- 20 control the movement of said member in one direction and to engage said member at another place and move it into position to operate the clutch mechanism.
- 25 13. In combination with a carrier frame and a supply holder rotatably mounted thereon, a spring tension let-off mechanism for said holder comprising a pivotally mounted holder-controlling device, a thread tensioning lever in constant operative engagement with said device, and a spring arranged to constantly act upon both the holder-controlling device and said lever.
- 30 14. In combination with a carrier frame and a supply holder rotatably mounted thereon, a spring-tension let-off mechanism for said holder comprising a pivotally mounted holder-controlling device, a thread tensioning lever in constant operative engagement with said device, and an adjustable spring arranged to constantly exert a regulated action upon both the holder-controlled device and said lever.
- 35 In testimony whereof, I have signed my name to this specification in the presence of two subscribing witnesses.
